Primary Examiner — Susan E Krakower(74) *Attorney, Agent, or Firm* — Thorpe North & Western LLP(57) **CLAIM**

The ornamental design for a head pad for backboard, as shown and described.

DESCRIPTION

FIG. 1 is an elevated, perspective view of the head pad for backboard in accordance with my invention;

FIG. 2 is a top view of the head pad for backboard of FIG. 1;

FIG. 3 is a bottom view of the head pad for backboard of FIG. 1;

FIG. 4 is a left side view of the head pad for backboard of FIG. 1;

FIG. 5 is a right side view of the head pad for backboard of FIG. 1;

FIG. 6 is a front end view of the head pad for backboard of FIG. 1; and,

FIG. 7 is a rear end view of the head pad for backboard of FIG. 1.

The broken lines shown in FIGS. 1-3 illustrate portions of the head pad for backboard which form no part of the claimed design.

1 Claim, 4 Drawing Sheets(56)
